SLATE SUPPORTING CLIP

Henry G. Bartsch, Washington, D. C.

Application January 30, 1937, Serial No. 123,291

15 Claims. (Cl. 108—33)

My invention relates to improvements in slate supporting clips, and has to do, more particularly, with the provision of a novel bracket or clip adapted to be associated with the standard perforations provided in slate shingles, and to be supported by means carried by the sub-roof in such fashion that accurate positioning of the replacement slate may be readily accomplished. Heretofore, it has been customary to replace a damaged or detached slate shingle with a new shingle anchored by means of an exposed nail, and to protect the exposed nail, and in part to conceal the head thereof, by means of a plastic coating of approximately the same shade as the slate of the roof. In order to effect such a repair, it is necessary to remove whatever remains of the damaged shingle, as well as such nails as were employed for its securement, by means of a tool known in the art as a "ripper". This tool includes a hook-like shank which is slipped up between the adjacent shingles which are disposed immediately above and immediately below the shingle to be replaced. By skillful manipulation, it is possible for the slater to effect complete removal of the two nails and such parts of the damaged shingle as remained secured thereby, without materially loosening or otherwise affecting the adjacent shingles.

The replacement shingle may then be slipped into the space previously occupied by the original shingle, but the securement thereof presents a complex problem for the reason that the pair of nail holes of the new slate, as well as the nails to be installed therein (in accordance with conventional practice) would be inaccessible because disposed a number of inches above the lower edge of the slate course which overlaps the course being repaired. For this reason, it has been the common practice of slaters to provide a third hole in the lower portion of the replacement slate, which hole is, when the slate is in proper position, disposed below the lower edge of the superjacent course. By the provision of this third, exposed hole, it is possible to place an anchoring nail therein, and to drive the same through the gap defined by the abutting side edges of the two shingles of the course below which are lapped by the single replacement shingle. In accordance with such practice, the head portion of the nail or nails employed for anchorage of the replacement shingle is exposed to the weather and will be corroded thereby. Moreover, even from the ground, such exposed nail heads are apparent, particularly where corroded matter from the nail head streaks the replacement shingle. In order

to prevent the corrosion of the nail head, and also to partially conceal it from view, slaters generally place, upon the exposed nail head, a dab of roofing cement corresponding as closely as possible to the color of the roof. It is but natural, therefore, that owners of buildings having slate roofs do not repair damage thereto unless absolutely essential because of bad leakage.

Considered more in detail, the problems and disadvantages of the conventional repair involve a number of considerations. In the first place, slate roofs are installed by hand and, however skillful the slater is, the variation in width of slate shingles, as well as the difficulty of placing the shingles by accurate measurement, renders it impossible to center the shingles of one course with respect to the shingles of the subjacent course, with the result that the line of abutment of two slates is not perfectly centered with respect to the shingle which partially overlaps these two shingles. The new nail hole which must be provided in the replacement slate by the slater is seldom disposed in the exact center of the slate, for the reason that this nail hole must be in alignment with the abutting edges of the two slates therewith so that the nail may enter in the gap between the two underlying slates to avoid breakage of either. New nail holes in slate shingles are formed by striking with a specially pointed hammer, and a flat, strong supporting surface, generally not available on the roof, is necessary for security against breakage of the slate. Slate shingles are, of necessity, suitable only for installation upon roofs of considerable pitch, and the maintenance of one's support on such a roof involves, also, such difficulty that the operation of accurately punching the new hole in a replacement slate while hanging upon such a roof is usually impossible. Accordingly, it is common practice for the slater to "try" the shingle, marking thereon the position at which the nail hole should be punched. The marked slate shingle is then lowered to an apprentice on the ground who punches the hole therein at the indicated position and then has the shingle passed up to the slater on the roof. Such work requires two men, and the major portion of the time spent by these is "waiting" time, during which no work is being done.

The protection and concealment of the nail head associated with the replaced slate also involves the problem of the prevention of smearing. In order to avoid the breakage of other slate of the roof, the slater must crawl over the roof with extreme care and in as prone a position as

possible to distribute his weight over a large area. This crawling about upon the roof, even when performed with the greatest of care, invariably results in smearing of dabs of cement placed upon the nail heads of previous repairs, because of the fact that the cement employed must be plastic when it is installed and must remain partially plastic after installation, if checking or cracking thereof is to be avoided. Slate roofs become extremely hot in the summertime, and such cement coverings upon the nail heads become soft and easily smeared. In addition, dust and debris such as leaves, become secured to such patches of cement and give the roof a splotchy, unclean appearance.

At least one inventor has attempted to eliminate the problems incident to the replacement of slate shingles by the use of a preformed clip adapted to be secured to the replacement slate by means extending through the conventional holes of the slate. One such form of clip is of T-shape, the leg portion of which is slightly curved so as to cause its lower end to abut the top or concealed edge of the slates underlying the replacement slate. Theoretically, such a clip would appear to meet the problem completely. However, as has been previously explained, slate roofs are laid manually without strict conformity to any definite degree of overlap of one course with respect to its underlying course. Moreover, the spacing between the nail holes and the lower edge of slate shingles, may vary widely even in the same roof, with the result that the length of the leg of such a clip would have to be determined accurately for each replacement, if alignment of the lower edge of the replacement slate, with respect to the lower edge of the entire course with which it is to be associated, is to be obtained. A replacement slate, the lower edge of which is disposed a slight distance above or below the normal line of its course, clearly stands out, even from the ground, so that standardization of such clips as just described is impossible if a satisfactory repair is desired.

With the prior art and its practices in mind, my invention has, for its purpose, several well defined objects. It is a primary object of my invention to provide a means and method of securing replacement shingles in slate roofs which is simple and rapid and which requires no apprentice on the ground.

It is an object of my invention to provide a means and method for replacing shingles in slate roofs in such fashion that the repair will be completely inconspicuous.

It is an object of my invention to provide a means and method for accurately replacing shingles in slate roofs which eliminates the necessity of an exposed nail head.

It is an object of my invention to provide a means and method for accurately replacing shingles in a slate roof which does not require the use of roofing cement.

It is an object of my invention to provide a novel means for securing replacement shingles in slate roofs which affords adequate support to the replaced slate.

It is an object of my invention to provide a novel means for accurately securing replacement shingles in slate roofs which will eliminate a large amount of breakage heretofore experienced.

It is an object of my invention to provide a means for replacing shingles in slate roofs which insures proper alignment of the replacement slate with respect to its companions.

It is an object of my invention to provide a clip or bracket for supporting replacement shingles which may be made in a standard size or sizes and which will have universal application to replacement slate shingles regardless of variations in their dimensions.

It is an object of my invention to provide a clip or bracket for supporting replacement slate shingles which is compact and light in weight, permitting the slater to carry a supply thereof upon his person.

It is an object of my invention to provide a clip or bracket for securing replacement slate shingles which is inexpensive to manufacture.

Finally, it is an object of my invention to provide a means and method of securing replacement slate shingles which requires no special skill and may be effected in a small fraction of the time heretofore required to obtain even a markedly inferior repair.

Further objects, and objects relating to economies and details of construction and installation will more definitely appear from the detailed description to follow. In one instance, I accomplish the objects of my invention by the means and method set forth by the following specification. My invention is clearly defined in the appended claims. Structures constituting preferred embodiments of my invention are illustrated in the accompanying drawings, in which:

Figure 1 is a top plan view of a portion of the conventional slate roof, one shingle of which has been replaced and is supported by a wire clip (shown in dotted lines) constituting one preferred form in which my invention is susceptible of embodiment;

Figure 2 is a vertical sectional view, on an enlarged scale, of the same construction and installation as shown in Figure 1, being taken on the line 2-2 thereof;

Figure 3 is a vertical sectional view of the elements and members shown in Figure 2, the replacement shingle, with its associated clip, being shown at an initial stage of its installation;

Figure 4 is a top plan view of a portion of a slate roof which has been prepared for reception of a replacement slate in accordance with my invention, the damaged slate and its nails having been removed and the new supporting nail having been set in position.

Figure 5 is an underside perspective view of the replacement slate and associated wire clip disclosed as a part of the constructions illustrated in Figures 1, 2 and 3;

Figure 6 is a plan view of a single replacement slate and associated clip fabricated from sheet stock, which clip constitutes a modified form of my invention;

Figure 7 is a vertical sectional view through a portion of a slate roof, one slate of which has been replaced and is supported by a clip of the type shown in Figure 6;

Figure 8 is a detail sectional view of the replacement slate clip shown in Figure 6, said view being taken on the line 8-8 thereof; and

Figure 9 is a perspective view of a nail gauge adapted to be utilized for the accurate location and setting of the nail upon which clips of the types shown in the foregoing figures are to be supported and anchored.

The same reference numerals refer to similar parts throughout the several views.

In a broad sense, my invention finds embodiment in a slate clip consisting of a thin body portion adapted to be disposed upon the under

surface of a shingle of slate or equivalent material, means extending upwardly from said body portion adapted to be extended through and engaged within the conventional pair of apertures with which such shingles are normally provided, and an anchoring portion at the lower end of said body portion adapted to engage a conventional roofing nail or the like which latter is so positioned with respect to the line constituted by the lower edges of the several slates comprising the course as to insure alignment of the lower edge of the slate to be replaced with the said course line. Preferably, the slate clip is of standard size, the aperture-engaging portions of which are adjustable to be engaged with shingles, the spacing of the holes of which may vary considerably. No adjustment need be available in the length of the body portion of the clip for the reason that the vertical positioning of the slate to be replaced with respect to other slates of its course may be accomplished by the proper location of the roofing nail, or other clip supporting element, with respect to the course line previously defined. The proper location of the roofing nail, as well as the spacing between the head thereof and the underlying slate surface of the immediately subjacent course of shingles is, in accordance with the broad concept of my invention, preferably determined by means of a simple tool. As will be understood from an inspection of the accompanying drawings, my invention is characterized by the fact that the roofing nail or other anchoring element is installed in the roof prior to the actual replacement of the repair shingle, and in the area of the roof which is exposed in the removal of the damaged slate and is covered and protected by the replacement slate after installation. Thus, the roofing nail mentioned is readily accessible for proper positioning and setting prior to the replacement of the shingle, but is concealed completely and protected from the elements after the new shingle has been installed. The head of the roofing nail may thus be disposed in appropriately spaced relation with respect to the top surface of the underlying shingles, and the nail engaging portion of the clip is especially formed so as to insure the travel of the clip upon the top surface of the nail head during the insertion of the slate and the engagement of the clip in interlocking relation beneath the head of the nail or the like when the slate has been brought to its final position of alignment with respect to its companions of the course.

With reference to the accompanying drawings in which I have illustrated two preferred forms of my invention, there is shown in Figure 1 a portion of a slate roof consisting of shingles 10a, 10b and 10c, of the repaired course; 11a, 11b and 11c of the subjacent course and 12a, 12b and 12c of the superjacent course. 10b is the replaced shingle. The conventional apertures x and y of the replaced shingle 10b are shown in dotted lines in Figure 1, being concealed by the overlapping shingles 12a and 12b of the superjacent course. Likewise, the shingle-supporting clip 13, constituting an embodiment of my invention, is shown in dotted lines, being similarly concealed by the shingles 10b, 12a and 12b. The anchoring and supporting nail 17 is also shown in dotted lines in Figure 1, being concealed by the lower half of the shingle 10b.

Referring now to the illustrations in Figures 1 to 4, inclusive, the slate clip 13 consists of a piece of wire stock of resilient steel, or the like,

bent into the form of a letter W. More specifically, the clip includes a pair of leg portions 14 which converge slightly toward their lower ends and are joined by a reverse bight portion 15, each of which legs terminating, at its upper end, in an offset double portion 16. The leg portions 14 are straight for the most part, the lower ends thereof, however, being slightly curved downwardly, for a reason to be explained. The bight portion 15 also curves slightly to conform to and lie in the same general geometrical surface as the adjacent, downwardly curved portions of the legs 14. The offset portions 16 of the clip consist, each, of a doubled section 16a generally parallel to the adjacent leg portion 14 and upwardly displaced, with respect thereto, a distance substantially equal to the thickness of the shingle with which it is associated. The doubling of the clip end extends downwardly from the portion 16b a distance approximately equal to the length of the portion 16a, thus, for this extent, constituting a double leg portion 14a.

By virtue of the resiliency in the legs 14, as well as in the inverted V or bight portion 15, the legs 14 may be sprung apart or together so as to be insertable in the standard perforations x and y of a conventional shingle. The "double" nature of the upper ends of the clip affords a snug fit of the offset portions of the legs 14 in the shingle holes, and, because the ends of the legs 14 are bent double, the extremity of each leg is naturally tapered or pointed, facilitating the insertion of the assembled clip and shingle.

For facilitating the proper location and securing of the replacement clip and slate, I have provided a special tool 18 illustrated in Fig. 9 of the accompanying drawings. This tool consists of a strip of thin sheet metal folded double and having its folded end bent upwardly to constitute a handle 18b. The plate-like base consists of the top and bottom plies 18e and 18f which are slightly spaced from each other to receive the ply 18g of roofing felt or similar shock-deadening material. The three sheets 18e, 18f and 18g are held in tight assembly by headed rivets 18h, the lower heads of which are preferably sunk flush with the undersurface of the tool. A notch 18a is cut into one edge of the tool base constituted by the three plies, which notch is adapted to receive a conventional headed roofing nail such as those 17 disclosed. The top surface 18c of the tool base is, either naturally or specially, treated to be erasably receptive of marking applied by a conventional graphite pencil (not shown). As will be apparent from the further description of the present invention, the tool 18 serves as a gauge for the proper location of nails 17 as well as a means for limiting the extent to which such nails are driven into the sub-roof.

The method of replacing slate shingles in accordance with this invention is as follows. As previously described in this specification, the roof is first prepared for the reception of the replacement by removal of the damaged shingle and the original nails employed for its securement. A clip 13 is then taken from the supply carried on the roof (presumably from the pocket of the slater), and the offset ends 16 of the clip legs are inserted through the conventional apertures x and y of the slate shingle to be employed as a replacement. This association of clip and shingle is clearly illustrated in Figure 5. The distance from the eye of the bight 15 to the extreme lower edge of the replacement slate is then measured. Preferably, this is determined by laying the tool

18 (shown in Fig. 9) upon the underside of the replacement slate 10b in such fashion that the notch 18a of the tool overlies the bight 15 of the clip, and the handle 18b is parallel to the lower edge of the shingle. While in this aligned relation, the slater marks, upon the top surface 18c of the tool, a line corresponding to the lower edge of the replacement shingle 10b. The tool 18 is then placed flat upon the surface of the subjacent shingles 11a and 11b, with the line previously marked upon the tool disposed directly above the base line of the course as defined by the lower edges of the shingles 10a and 10c. With the tool 18 thus flatly disposed upon the shingles 11a and 11b in such fashion that the left edge 18c of the tool is directly aligned and disposed above the adjacent lateral edges of the shingles 11a and 11b, a conventional roofing nail 17 is placed in the notch 18a of the tool and driven home upon the top surface 18c of the tool. The tool 18 is then removed from engagement with the thus-set nail 17 and, the thickness of the tool being equal to, or slightly in excess of, the thickness of the clip 13, the head of the nail 17 is disposed in correspondingly-spaced relation with respect to the upper surface of the shingles 11a and 11b of the subjacent course.

The roof is now in condition for the reception of the replacement shingle and its clip, and the shingle 10b, together with the clip 13 attached thereto, is slipped upwardly into the space which it is to occupy, as illustrated in Figure 3 of the drawings. As will be appreciated from an inspection of this figure, the curvature provided in the lower ends of the legs 14, as well as in the bight portion 15, induces the bight 15 to cam up upon the top surface of the nail as the shingle is moved upwardly beyond the position illustrated in Figure 3 into a position even more elevated than illustrated in Figure 2. The slater then bears downwardly upon the exposed portion of the shingle 10b with his hands and forces the shingle 10b to descend, causing the bight portion 15 of the clip to extend beneath the head of the nail 17 into final straddle-engaged relation with respect to the nail, as shown in Figure 2. It will be noted that the final setting of the bight 15 upon the nail 17 causes the curvature at the lower end of the clip to be reduced or eliminated, assuring a snug and rattle-free securement of the clip and its shingle. As has been previously explained in this specification, the crack defined by the adjacent side edges of the shingles 11a and 11b is not, in common practice, always centered with respect to the lapping shingle 10b. Even where such an inaccuracy is large, assurance of alignment of the bight 15 with the nail 17 may be accomplished by appropriate bending of the legs 14 of the clip to displace the bight 15 to one side or the other of the center line of the shingle 10b. Where this inaccuracy is slight, the forked nature of the lower end of the clip, as well as the inherent resiliency of the legs 14, may be adequate to compensate for lack of alignment between the shingles 10b and 11a and 11b. The abutment of the side edges of the slate 10b with the slates 10a and 10c of the course is adequate to prevent lateral displacement of the shingle 10b under such conditions. The doubled construction of the upper ends 16 of the clip provides a strong resistance to deformation of the offsets therein, as well as a snug fit of the clip in the apertures x and y of the replaced slate.

75 The thickness of the clip is so slight that the

replaced shingle will not be so elevated above the roof surface as to permit the access of moisture to the nail 17 or the clip, nor is the slight difference in level between the replaced shingle and others of the course so perceptible as to be apparent.

In Figures 6, 7, and 8, I have illustrated a modified form of clip for performing the same function as that disclosed in the previous figures. This clip 23 is formed of thin sheet metal of relatively stiff, but resilient, character. In this embodiment of the invention the body portion 24 of the clip is constituted by a single plate instead of the leg portions 14 of the wire-type clip. The body portion 24 is preferably of triangular form, the broad or upper end thereof being cut to provide a multiplicity of tongues 26, a selected pair of which may be bent upwardly and extended through the apertures x and y of a conventional shingle, and the terminal portions 26a of which tongues may be bent down upon the upper surface of the slate shingle to assemble the clip with the shingle. As distinguished from the previously described wire clip 13, the aperture engaging means of the clip 23 preferably comprise, each, a pair of tongues 26, whereby a snug fit of the securing means in the apertures x and y is assured. Moreover, by making the tongues 26 of a width approximating one-half the diameter of the apertures x and y, it is possible to locate the clip 23 in any desired lateral displacement with respect to the center of the replacement shingle. There is thus obtained a lateral adjustability of the clip with respect to the shingle with which it is to be associated, corresponding to the lateral displacement which may be effected in the clip 13 by reason of the springiness of the legs 14 or, in extreme instances, by a permanent bending of one or both of the legs 14. The lower end of the clip 23 is constituted by a bifurcate extension 25 of the body portion 23 of the clip, which extension 25 is, like the bight portion 15 of the previously described clip, slightly downwardly curved to insure engagement of the terminal fork beneath the head of the roofing nail 17 driven into the sub-roof in the manner previously described.

The mode of use of the clip 23 disclosed in Figures 6, 7, and 8 of the drawings is substantially identical with that of the clip 13, the only distinction being that the tongues 26 are given their final bent form after their insertion in the apertures x and y of the shingle to be employed as a replacement. Similarly, as has been explained, lateral displacement of the clip portion 25 with respect to the center line of the replacement slate is effected by the selection of appropriate ones of the securing tongues for insertion in the apertures x and y of the shingle.

I am aware that my invention is susceptible of embodiment in various structural forms, the illustrated clips being disclosed solely as examples of a broad inventive concept. Numerous changes in size and form will appear to those skilled in the art upon familiarization with the invention as set forth in the preceding description. For example, types of head studs other than the roofing nail 17 may be employed. In some instances, it may be found desirable to substitute a conventional wood screw for the nail 17 illustrated. The tool 18 which is so desirable for the proper practice of my invention may, likewise, be embodied in various forms. For example, in lieu of the notch 18a at one edge of the tool, there may be substituted a keyhole slot 18z disposed at approximately the center of the base of the tool.

Such a slot has the advantage of assuring parallelism of the nail head with the surface of the underlying slate shingles 11a and 11b for the reason that a more extensive "anvil" surface is provided for the nail head. Removal of the tool from engagement with the nail after its setting is, with such a slot construction, effected by pushing the tool upwardly so that the large circular portion of the slot 18z will clear the head of the nail. The large circular portion of the slot must, therefore, be of ample size to clear the largest nail head which may be expected in this work. Obviously the handle 18b of the tool may take various forms and may, if desired, be located along a side of the tool instead of at the lower end thereof. In this instance, it would probably be preferable to make the handle as a separate part and to attach it to the tool base 18c by means of rivets or other fastening means. Preferably, the tool should be of such length that the upper and lower ends thereof will overlie those portions of the shingles 11a and 11b which are in contact with the sub-roof and the next lower course of shingles. This proportioning of the tool, together with the shock absorbing nature of the interposed ply 18g thereof, operates to protect the slate shingles 11a and 11b from breakage during the setting of the nail 17.

In the specification I have described the nail engaging portions 15 and 25 of the illustrated clips as "bifurcate", and it is intended that this term shall apply with equal aptitude to both the sheet metal and the wire types of clips. Likewise, I have described the two legs 14 of the wire type clip as the "body portion". These elements perform the function of the solid body 24 of the sheet metal type clip. The term "slate shingle" is also to be given an interpretation of sufficient breadth to include such flat shingles as are being manufactured synthetically from mixtures of asbestos and Portland cement or the like. In this specification I have also described the pre-set relationship of the nail 17 as one in which the head of the nail is spaced from the underlying surfaces of the shingles 11a and 11b, a distance "corresponding" to the thickness of the clip to be supported thereon. In practice, it has been found desirable to give the base 18c of the tool 18 a thickness slightly greater than the thickness of the slate clip, to facilitate the insertion of the bifurcate portion of the clip beneath the nail 17. Where a clip having a slightly downwardly curved end is employed, the curvature of this end is adequate to insure a snug fit of the clip with the stud 17, notwithstanding the fact that the thickness of the clip at this point may be slightly less than the spacing between the nail head and the top surface of the underlying slates 11a and 11b. The foregoing, and other changes and factors relating to the present invention, will be apparent to those skilled in the art and familiar with the present invention. Accordingly, I claim my invention broadly as indicated by the appended claims.

What I claim is:

1. A standardized clip for the support of slate shingles of the conventional type provided with a spaced pair of nail-receptive apertures, comprising: a body portion adapted to flatly underlie the under surface of the shingle with which it is to be associated, means at the upper end of said body portion disposable through said shingle apertures to secure said clip to the shingle, and means at the lower end of said body portion adapted to lie flatly upon the top surface of shingles of the subjacent course when lapped by the

first-mentioned shingle, said last-mentioned means being engageable with a headed stud pre-set in the sub-roof with its head in slightly spaced relation with respect to said top surface of said subjacent shingles. 5

2. A standardized clip for the support of slate shingles of the conventional type provided with a spaced pair of nail-receptive apertures, comprising: a body portion adapted to flatly underlie the under surface of the shingle with which it is to be associated, means at the upper end of said body portion disposable through said shingle apertures to secure said clip to the shingle, and means at the lower end of said body portion adapted to lie flatly upon the top surface of shingles of the subjacent course when lapped by the first-mentioned shingle, said last-mentioned means having inherent flexibility and a barely perceptible downward curvature such as to insure its engagement and association with a headed stud pre-set in the sub-roof with its head in slightly spaced relation with respect to said top surface of said subjacent shingles. 10 15 20

3. A standardized clip for the support of slate shingles of the conventional type provided with a spaced pair of nail-receptive apertures, comprising: a body portion adapted to flatly underlie the under surface of the shingle with which it is to be associated, means at the upper end of said body portion disposable through said shingle apertures to secure said clip to the shingle, and a bifurcate extension at the lower end of said body portion adapted to straddle-engage and be supported by an upstanding headed stud pre-set in the sub-roof. 25 30 35

4. A standardized clip for the support of slate shingles of the conventional type provided with a spaced pair of nail-receptive apertures, comprising: a body portion adapted to flatly underlie the under surface of the shingle with which it is to be associated, means at the upper end of said body portion disposable through said shingle apertures to secure said clip to the shingle, and a resilient, slightly downwardly curved, bifurcate extension at the lower end of said body portion adapted to straddle-engage and be supported by an upstanding headed stud pre-set in the sub-roof. 40 45

5. In a slate roof construction, a sub-roof, courses of slate shingles secured to said sub-roof in staggered lapping relation, a shingle constituting one element of one of said courses, said shingle having a spaced pair of apertures formed therein lying in a horizontal line parallel to and near the upper edge thereof, and means for securing said shingle in position, said securing means including a headed stud set in said sub-roof, the shank of which stud extends between the adjacent side edges of the lapped portions of the two shingles of the underlying course and the head of which stud is slightly spaced above said lapped shingle surface, and a clip having means adjacent its upper end engaged within the spaced apertures of said first-mentioned shingle and means at its lower end flatly disposed upon said lapped shingle surfaces beneath and snugly engaged with the head of said stud. 50 55 60 65

6. In a slate roof construction, a sub-roof, courses of slate shingles secured to said sub-roof in staggered lapping relation, a shingle constituting one element of one of said courses, said shingle having a spaced pair of apertures formed therein lying in a horizontal line parallel to and near the upper edge thereof, and means for securing said shingle in position, said securing 70 75

- means including a headed stud set in said sub-roof, the shank of which stud extends between the adjacent side edges of the lapped portions of the two shingles of the underlying course and the 5 head of which stud is slightly spaced above said lapped shingle surface, and a clip having means adjacent its upper end engaged within the spaced apertures of said first-mentioned shingle and having a bifurcate stud-engaging portion at its 10 lower end flatly disposed upon said lapped shingle surfaces and snugly straddle-engaged with said stud beneath its head.

7. In a slate roof construction, a sub-roof, courses of slate shingles secured to said sub-roof 15 in staggered lapping relation, a shingle constituting one element of one of said courses, said shingle having a spaced pair of apertures formed therein lying in a horizontal line parallel to and near the upper edge thereof, and means for securing said shingle in position, said securing means including a headed stud set in said sub-roof, the shank of which stud extends between the adjacent side edges of the lapped portions of the two shingles of the underlying course and the 20 head of which stud is slightly spaced above said lapped shingle surface, and a clip comprising a body portion adapted to flatly underlie the under surface of said first mentioned shingle, means at the upper end of said body portion engaged with 25 30 in the spaced apertures of said shingle, and a resilient, slightly downwardly curved, bifurcate extension at the lower end of said body portion bearing upon said lapped shingle surfaces and snugly straddle-engaged with said stud beneath 35 its head.

8. A standardized clip for the support of slate shingles of the conventional type provided with a spaced pair of nail-receptive apertures, comprising: a piece of relatively stiff resilient wire stock 40 having the general form of a letter W, the two upstanding arms of which terminate in similar shingle-anchoring offsets and are laterally springable with respect to each other so as to be readily engageable in the variously spaced apertures 45 of conventional slate shingles, and the bight or inverted V base portion of said clip being relatively small and low with respect to the size of the entire clip and being adapted to straddle-engage and be supported upon a headed stud set 50 in the portion of the sub-roof covered by the exposed portion of the shingle when installed.

9. A standardized clip for the support of slate shingles of the conventional type provided with a spaced pair of nail-receptive apertures, comprising: a piece of relatively stiff resilient wire stock having the general form of a letter W, the two upstanding arms of which terminate in similar, rigid, double, shingle-anchoring offsets and are laterally springable with respect to each 55 other so as to be readily snugly engageable in the variously spaced apertures of conventional slate shingles, and the bight or inverted V base portion of said clip being relatively small and low with respect to the size of the entire clip and 60 being adapted to straddle-engage and be supported upon a headed stud set in the portion of the sub-roof covered by the exposed portion of the shingle when installed.

10. A standardized clip for the support of slate shingles of the conventional type provided 70 with a spaced pair of nail-receptive apertures, comprising: a piece of relatively stiff resilient wire stock having the general form of a letter W, the two upstanding arms of which lie, for 75 the most part, in a common plane, yet terminate,

at their upper ends, in similar upstanding offsets and are laterally springable with respect to each other so as to be readily engageable in the variously spaced apertures of conventional slate shingles, said arms curving slightly downwardly 5 at their lower ends, and the bight or inverted V base portion of said clip being relatively small and low with respect to the size of the entire clip and having a curvature corresponding to the curvature of the adjacent ends of said clip arms 10 whereby said bight portion may be readily hooked, saddle fashion, upon a headed stud pre-set in the portion of the sub-roof covered by the exposed portion of the shingle when installed.

11. A standardized clip for the support of slate shingles of the conventional type provided with a spaced pair of nail-receptive apertures, comprising: a thin, sheet metal body portion 15 adapted to flatly underlie the under surface of the shingle with which it is to be associated, hook means formed in the upper end of said body portion disposable through said shingle apertures to secure said shingle to said clip, and a bifurcate portion constituting an extension of the lower end of said body portion adapted to 20 straddle-engage and be supported by an upstanding headed stud pre-set in the sub-roof.

12. A standardized clip for the support of slate shingles of the conventional type provided with a spaced pair of nail-receptive apertures, comprising: a thin, sheet metal body portion adapted to flatly underlie the under surface of the shingle with which it is to be associated, a series of 25 tongues formed in the upper end of said body portion, a pair of which are adapted to be bent 30 upwardly and offset into interlocked engagement with the apertures of the shingle to be mounted, and a bifurcate portion constituting an extension of the lower end of said body portion adapted to 35 straddle-engage and be supported by an upstanding headed stud pre-set in the sub-roof.

13. A standardized clip for the support of slate shingles of the conventional type provided with a spaced pair of nail-receptive apertures, comprising: a thin, sheet metal body portion 45 adapted to flatly underlie the under surface of the shingle with which it is to be associated, hook means formed in the upper end of said body portion disposable through said shingle apertures to secure said shingle to said clip, and 50 a resilient, slightly downwardly curved bifurcate extension at the lower end of said body portion adapted to snugly straddle-engage and be supported by an upstanding headed stud pre-set in the sub-roof.

14. A standardized clip for the support of slate shingles of the conventional type provided with a spaced pair of nail-receptive apertures, comprising: a thin, sheet metal body portion 55 adapted to flatly underlie the under surface of the shingle with which it is to be associated, a series of tongues formed in the upper end of said body portion, a pair of which are adapted to be bent upwardly and offset into interlocked engagement with the apertures of the shingle to be 60 mounted, and a resilient, slightly downwardly curved bifurcate extension at the lower end of said body portion adapted to snugly straddle-engage and be supported by an upstanding headed stud pre-set in the sub-roof.

15. The method of replacing a damaged slate shingle in a conventional slate roof consisting of a plurality of shingle courses secured to a sub-roof in staggered lapping relation, which comprises: removing such parts of the damaged shin- 75

gle and its fastening elements as remain, forming a flat clip with a bifurcate lower portion, securing the upper end of said clip to the under-side of the replacement shingle through the nail-receptive apertures conventional in slate shingles, measuring the distance from the notch of said bifurcate clip portion to the lower edge of the clip-associated shingle, driving a headed stud into said sub-roof through the crack between the adjacent side edges of the two shingles of the subjacent course which are to be lapped by said replacement shingle, said headed stud being driven so far into said sub-roof as to provide a space, between the under surface of its head

and the top surface of said lapped shingles, equal to the thickness of said clip, and being located at a distance from the lower edge of the damaged course equal to the previously determined distance from said clip notch to the lower edge of said clip-associated shingle, pushing said clip-associated shingle up into and beyond the space which it is to occupy so that the bifurcate end of its clip clears said headed stud, and, finally, retracting said shingle and its clip to bring the bifurcate lower end of the latter into straddle-engagement with the upstanding portion of said headed stud. 5 10

HENRY G. BARTSCH.
